US0D1032735S

(12) **United States Design Patent** (10) **Patent No.:** **US D1,032,735 S**
(45) **Date of Patent:** **** Jun. 25, 2024**

(54) **FOAM MACHINE**

(71) Applicant: **Yongji Tan**, Yiwu (CN)

(72) Inventor: **Yongji Tan**, Yiwu (CN)

(**) Term: **15 Years**

(21) Appl. No.: **29/912,808**

(22) Filed: **Sep. 23, 2023**

(51) **LOC (14) Cl.** **21-01**

(52) **U.S. Cl.**

USPC **D21/401; D26/65**

(57) **CLAIM**

The ornamental design for a foam machine, as shown and described.

DESCRIPTION

FIG. 1 is a perspective view of a foam machine showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a rear, bottom, and right side perspective view thereof.

The dash-dash broken lines in the drawings depict portions of the foam machine that form no part of the claimed design.

1 Claim, 7 Drawing Sheets
